BOX MAGAZINE FOR AUTOMATIC LOADING
WEAPONSFritz Herlach and Theodor Rakula, Solothurn,
Switzerland, assignors to Waffenfabrik Solo-
thurn A.-G., Solothurn, Switzerland, a corpora-
tion of SwitzerlandApplication April 17, 1933, Serial No. 666,598
In Germany July 12, 1932

7 Claims. (Cl. 89—33)

The invention relates to a box magazine for use in automatic firearms. Its object is to prepare quickly for firing again a magazine which has been fired until empty so as to eliminate 5 time-wasting filling operations and to render the troublesome carrying of filled magazines or special filling devices unnecessary. The magazine may be fixed and remain permanently on the weapon, or, preferably, it may be an interchangeable, de- 10 tachable magazine.

For this purpose, the magazine according to the invention has a casing with an opening in one wall thereof to allow a cartridge pack to be inserted, a cover for said opening, and a spring 15 pressed feeder operable from the outside to force the cartridge forward against retaining lips at the mouth of the magazine, whence it is thrust forwards by a part of the weapon proper. Further, according to the invention and in contrast to the known arrangements with a positive 20 control between the feeder and the cover, the magazine is provided with a latch device which alternately secures the feeder, which has been withdrawn into its tensioned position, against 25 flying forward prematurely, or secures the cover, which has been brought into closed position, against the action of a spring. In the known arrangements wherein the return of the feeder depends on the opening of a magazine cover, a 30 special locking device is required for the cover to oppose the action of the feeder spring when it is in its open position and which, in order that the magazine may be closed, must be specially released by hand. This is avoided in the arrangement 35 according to the present invention which simplifies both the manipulation to supply ammunition and the construction of the apparatus itself. After the withdrawal of the feeder and the insertion of the pack of cartridges only a 40 closing movement of the cover is required.

For the insertion of cartridge packs into the magazine it is advantageous to arrange the magazine on the weapon, first of all in known manner disposed horizontally with one of its wider sides 45 upwards, and then to construct this side as a cover adapted to pivot about the end of the magazine on the weapon side. The magazine may be adapted to be attached and removed, for which purpose it is advisable for it to be constructed as 50 a metal casing with a steel mouthpiece in front. The mouthpiece is thereby able to withstand the great stress caused by frequent application and removal of the magazine and is also of sufficient strength to co-operate with the retaining devices 55 engaging therewith for connecting the magazine

to the weapon and finally also to serve as support for the various members and the articulation of the hinged cover to be arranged thereon.

The withdrawal of the feeder into its tensioned position for freeing the space needed by the pack of cartridges in the magazine is facilitated by a curved lever which is pivotally mounted about a hinge on the outer, front corner of the magazine and engages a projection on the feeder, and which lever is provided with a handle. The 10 feeder is tensioned by a pull on the curved lever, which is in a convenient position for the gunner. This curved lever slides along the projection of the feeder, presses the latter outwards and as the retraction of the feeder progresses thereby increases the spring resistance, and the distance 15 of the pivotal point of the lever from its point of engagement on the feeder becomes constantly smaller so that the effort to be exerted on the handle during the entire tensioning process, in 20 spite of increasing tension of the feeder spring, remains approximately the same, and is moderately low.

The pack of cartridges provided for the replenishment of ammunition may be arranged for 25 one or more rows, for instance with zig-zag positioning of the cartridges. It contains the entire charge, for a magazine arranged in a clip from which the cartridges are thrust by the 30 magazine-feeder up to the retaining lips of the magazine mouth and thus into the range of the member of the weapon which sweeps them into the chamber in the barrel of the weapon. Locking means for securing the cartridges in the clip during transport until use in the magazine are 35 moved aside automatically by a device actuated by the movable magazine wall or cover, to such an extent that the cartridges can be thrust out of the clip by means of the magazine-feeder, without any special expenditure of force. The 40 emptied clip is automatically ejected when the magazine is opened by, for instance, in consequence of its weight falling out of the magazine through an opening at the bottom thereof.

The new magazine may be used for holding 45 grooved cartridges or rim cartridges. In the case of the first-mentioned type of cartridges, in order to prevent the foremost cartridge located in the range of the bolt-members of the weapon from getting out of position behind the rim of the following second and third cartridges, separators of known type may be arranged on the magazine or on the weapon. A plurality of such magazines may, of course, also be used on a weapon, 50 55

by fitting, for instance, a magazine on either side of the weapon.

Further details of the magazine and the appropriate cartridge-packs are explained by 5 means of the example of construction shown in the drawings:

In the drawings:

Fig. 1 is a plan of a detachable magazine fitted on the weapon with the lid open;

10 Fig. 2 is a longitudinal section along the line 2—2 of Fig. 1;

Fig. 3 is a longitudinal section along the line 3—3 of Fig. 1;

15 Fig. 4 is a cross-section along the line 4—4 of Fig. 1;

Figs. 5 to 8 show an example of construction of a two-row cartridge packing for grooved cartridges, in which,

20 Fig. 5 is a diagrammatic side view of a cartridge clip with cartridges,

Fig. 6 is a diagrammatic end view thereof,

Fig. 7a is a diagrammatic top view of the left end of Fig. 5,

25 Fig. 7b is a diagrammatic top view of the right end of Fig. 5, and

Fig. 8 is a diagrammatic end view of a modified clip; and

30 Figs. 9 and 10 are an example of construction of a two-row packing for rim cartridges, in which,

Fig. 9 is a diagrammatic side view of a cartridge clip with cartridges, and

Fig. 10 is a diagrammatic end view thereof.

The magazine consists of a mouthpiece 1, the 35 frame 2 open at the upper side, and the end plate 3, which parts are preferably connected together to form a rigid casing by welding.

40 The mouthpiece 1 which is of steel and is provided with strong walls, carries in front resilient but stiff retaining lips 4 by which the cartridges are held in known manner in such a position that they can be seized singly by the appropriate 45 part of the weapon (the lock member 5) and can be swept in their longitudinal direction out of the magazine into the chamber 6 of the barrel of the weapon. On the mouthpiece 1 there are also fitted the means for connecting the magazine to the weapon.

45 As shown in Fig. 1 this is a member 7 of semi-circular cross-section on the front side of the magazine, which, together with a bearing groove on the weapon which receives it, forms a self-releasing pivot joint for the swinging forward of the magazine out from its position of use. The 50 magazine is secured in this position by a flat-sided bolt 9 which engages with a catch 8 on the rear side of the mouthpiece, and which is pivotally mounted in the weapon, which bolt is held turned into the locking position by a spring, not 55 shown, or can be made arrestable in the released and locked position by suitable locking means.

60 An abutment 10 co-operating with the magazine projection 8 prevents the magazine from swinging too far into the weapon. If the bolt 9, the handle of which (not shown) is located in easy reach of the thumb of the gunner's hand which is around the magazine, is turned into its release position, the magazine can be turned forward about the member 7 until the projection 8 has passed the bolt 9, and then withdrawn from the weapon. For purposes of attachment the magazine is first of all placed with its member 7 in the magazine bearing of the weapon, then 65 swung back so far that the projection 8 engages

70 behind the bolt 9. Further, the magazine mouthpiece carries the attachment and guide members for the cover which in the example in the drawings is a hinged cover 11 adapted to close the open top of the magazine. This cover is adapted to pivot about a hinge formed by two eyes 12 on the mouthpiece and two eyes 13 on itself with the appropriate bolt 14. The pretensioned spiral spring 15 mounted between the eyes 13 on the bolt 14 tends to hold the cover 11 constantly open. 10

15 In the magazine frame 2, the feeder 16 is guided by means of its sides 17 and 18 and by two lateral surfaces 19 of a bearing member 20 welded thereto. These surfaces 19 are guided in a slot 21 in the bottom side of the magazine. Further, the bearing member 20, by means of two surfaces 22, engages under the ridge 23 surrounding the slot 21 whereby the feeder is secured against falling out of the magazine when the cover 11 is open. In order that it may be 20 possible to insert and remove the feeder, the slot 21 has in its middle part a widened portion 24 through which the bearing member 20 of the feeder can be passed.

25 On the projecting pin of the bearing member 20 there is mounted a grooved roller 25 in the groove of which a tension lever 26 is placed when the feeder 16, against the pressure of the feeder spring 27, is to be moved backwards in the magazine. The handle 28 of the lever 26 is located behind the rear side of the magazine and the lever arm 26 of such curvature that the pressure exerted by the latter on the feeder roller 25 is directed approximately in the direction of movement of the feeder. The lever 26 itself is pivotally mounted in a bearing lug 29 welded to the front outer corner of the magazine. Thus when the feeder is thrust back against the constantly increasing force of the spring 27, the distance of the roller 25 from the 30 pivoting point 29 and, therefore, also the resisting torque about this point becomes constantly smaller, and only a uniform moderate force need be applied by the operator to the lever handle 28. A spiral spring 29a in the lug 29 automatically returns the lever 26 to and holds it in its initial position shown in Fig. 1, where it rests against an attachment 65 on the magazine. The spring 27 is fixed and supported in the feeder by bent members 30 in the latter, 35 its other end resting against the end plate 3 of the magazine; pins 31 and 32 fixed to the end plate 3 prevent the outer end of the spring from 40 springing out when the cover 11 is open.

45 The end plate is provided with a recess 33 in which, on a bolt 34, a double armed latch 35 is mounted, and held by a spring 36 supported against the end plate 3 in its normal position, in which it rests with its surface 37 against the end plate 3 of the magazine.

50 When the feeder 16 is withdrawn an inclined surface 38 of its bearing member 20 comes into contact with the projection 39 on the lower arm of the latch 35. The latter is thereby swung downwards against the pressure of its spring 36. The feeder 16 can now be withdrawn a little further in the magazine than is necessary for the passing of the lower arm of the latch 35 through the slot 40 located in the bearing member 20 and for the subsequent engagement of the projection 39 in front of the surface 41 of the bearing member 20 and with such withdrawal the inclined surface 38 of the bearing member 20 also comes into contact with the inclined surface 42 on the lower arm of the latch 35. 55

Thus the latter is swung downwards further than is possible by the engagement of its projection 39 with the surface 38. If then the pressure withdrawing the feeder ceases, under the influence of the feeder spring, the feeder again slides forwards until the projection 39 of the latch 35, which springs up under the pressure of the spring 36 engages in front of the surface 41 of the bearing member 20, and prevents the feeder from proceeding further forward. Previously, the latch 35, by means of the projection 43 of its upwardly directed arm, had held the lid 11, which tends to rise under the action of the spring 15, in its closed position. In consequence of the turning of the latch 35 which occurs on the return of the feeder 16 when the surfaces 38 and 42 engage, the cover 11 is released and springs up into its open position as shown in the drawings.

The arrangement of the second inclined surface 42 on the lower arm of the latch ensures the satisfactory operation of the locking device and enables accurate formation of the locking surfaces on the lever projections 39 and 43 to be obtained with sufficiently large permissible tolerance. The latter projection 43 located on the upper arm of the latch 35, on the re-closing of the cover 11, comes into contact with the inclined surface 44 of the retaining slot 45 in the cover and is forced aside, and, before its subsequent snapping back into position to hold the cover springs the lever 35 so far that the projection 39 releases the tensioned feeder so that it can fly forward. Now the depth of the engaging surface of the projection 39 is greater than that of the projection 43, which, again, for the disengagement of 43 from the surface 44 where it would be inconvenient, is compensated by the slight extra turn of the lever 35 produced by means of the inclined lever surface 42 in co-operation with the inclined surface 38 on the feeder.

The cartridge pack intended for filling a magazine of the type described above is of the two-row type and completely charges the magazine. Its length is such that it fits in the magazine space which is freed when the feeder 16 is withdrawn and the cover 11 opened, while leaving a free space in front of it in the magazine mouthpiece 1, which space accommodates the cartridges thrust out in loose order from the pack. It is preferable to arrange for the cartridge pack to accommodate an even number of cartridges and for their two ends to be arranged symmetrically to one another, so that the pack can be placed in the magazine either side uppermost.

The clip 46 or 47 which holds the cartridges of the pack together, according to the form of construction shown in Figs. 5 to 10, consists of a U-shaped plate of steel, tin or brass, the side walls of which—as shown in Fig. 8—can be stiffened by channels 48, and having two longitudinally directed inner projections 49 (Fig. 6), or alternatively two longitudinal grooves 50 as shown in Fig. 10 co-operating with the cartridge grooves or rims respectively to prevent them from falling out in the direction of the longitudinal axis of the cartridges. According to Fig. 10, the rim-cartridges are, by means of a step 51 in the bottom of the clip 47, arranged in two adjacent rows at different levels; the height of this step 51 is equal to the thickness of the rims of the cartridges and makes it possible for the two rows of cartridges to be held closely to-

gether, so that they are held together as securely as in the case of rim cartridges without such a step being provided in the clip. At both its ends, namely at diagonally opposite corners, the cartridge clip 46 or 47 carries lips 52 formed by cutting away at the ends of the clips the portions containing the internal projections 49 or the grooves 50, the lips thus formed being bent inwards. Each lip embraces the outermost cartridge at the respective end of the clip and prevents the cartridges from being removed unintentionally from the clip. These lips are provided with extensions 53 which stand out from the clip, one of which extensions, after the frame has been placed in the magazine, engages under the projection 54 of a bell crank lever 56 adapted to pivot about a bolt 55 mounted in the magazine frame.

When the magazine lid is open this bell crank lever, owing to the pressure of its spring 56a, protrudes with its second arm 57 beyond the upper edge of the magazine frame 2, so that when the cover 11 is closed it is depressed thereby and with its projection 54 bends out the lip 52 at the front end of the cartridge clip 46 or 47 from the path of the cartridges by pressure on the extension 53. This takes place in the last part of the closing movement of the cover and the simultaneously released feeder can thrust the cartridges, without encountering any considerable opposition, from the cartridge clip against the retaining lip of the magazine mouthpiece.

The cartridge clip 46 or 47 may be secured against longitudinal displacement in the magazine by one end of the clip resting against the projection 54 of the bell crank lever 56, and the other or outer end by a projection 58 fixed in the magazine frame. This arrangement may be effected in such a manner that when the cartridge clip is in contact with the projection 54 a free space exists between its outer end and the projection 58, the cartridge clip is taken back through this space when the feeder 16 is withdrawn, in order to move out of the range of the projection 54 of the bell crank lever 56.

In order that the clip 46 or 47 may be secured in the magazine against turning or transverse displacement, also, support surfaces are provided in the magazine for the longitudinal edges 59 of the side wall parts of the cartridge clip. The lower supporting surface is formed by the limiting edge 60 of an opening 61 in the bottom side of the magazine, permitting in known manner the empty cartridge clip to fall out of the magazine (Fig. 1). Further, the cover 11 has a groove 62, against the longitudinal edge 63 of which the top edge 59 of the cartridge clip rests when the lid is closed. A cartridge clip 46 or 47 emptied by continuous ejection of its cartridge under the pressure of the magazine feeder during firing, falls down through the opening 61, as soon as the feeder which has moved forward between the side walls of the clip has been withdrawn into its rear position for the refilling of the magazine.

A magazine can, of course, also be recharged when removed from the weapon, and moreover for this purpose loose cartridges may be used instead of cartridge packs. In order that the lock of the weapon may remain automatically in its open position after a magazine has been emptied by firing, and so that the firing can be continued immediately after the magazine has been refilled, the magazine feeder 16 strikes in known manner, for instance, with its bearing member 75

20 in its front end position, against the oppositely located projection 64 of a lever 67 adapted to pivot about a bolt 66 in the attachment 65 of the magazine frame 2. This lever, with its other projection 5 68, presses on an interrupter lever 69 mounted in the weapon, which in its turn prevents any possibility of firing or by direct locking of the breech bolt the latter, after the last shot has been fired from the magazine, is caught and held in its backward open position.

10 We claim:

1. A cartridge magazine for firearms comprising a casing removably attached to the firearm and having an opening for the insertion of a cartridge pack into the casing, means at the front 15 end of the casing for guiding cartridges into the breech of the firearm, a cover for said opening, means urging the cover to open position, a cartridge feeder movable in said casing, means urging the feeder in the direction of the guide means, and a latch cooperating with the cover and the 20 feeder to retain the feeder at the rear end of the casing while releasing the cover and to release the feeder when said latch engages the cover to 25 close the opening.

2. A cartridge magazine for firearms comprising a casing extending transversely from the bridge of the firearm and removably attached thereto, said casing having an opening in its top 30 for the insertion of a cartridge pack, means at the bridge end of the casing for guiding cartridges into the bridge of the firearm, a cover for said opening hinged to the casing at the bridge end thereof, means urging the cover to 35 open position, a cartridge feeder movable in said casing, means urging the feeder in the direction of the guide means, and a latch cooperating with the cover and feeder to retain the feeder at the outer end of the casing while releasing the cover 40 and to release the feeder when the said latch engages the cover to close the opening.

3. A cartridge magazine for firearms comprising a casing removably attached to the firearms and having an opening for the insertion of a cartridge pack into the casing, means at the front 45 end of the casing for guiding cartridges into the breech of the firearm, a cover for said opening, means urging the cover to open position, a cartridge feeder movable in said casing, means urging the feeder in the direction of the guide 50 means, a latch lever having an arm engaging the feeder and an arm engaging the cover, projec-

tions on the feeder and cover cooperating with said arms and so arranged that a greater movement of the lever is required to release the cover than to release the feeder, and ramps on the feeder and the lever arm engaging the same effective upon an auxiliary movement of the feeder to impart such greater movement to the latch lever.

4. A cartridge magazine for firearms comprising a casing having an opening for the insertion of a cartridge pack into the casing, means on the casing for guiding cartridges into the breech of the firearm, cartridge retaining lips on the guide means, means for detachably securing the casing in operative position on the firearm, a cover for said opening pivoted to the magazine, a latch cooperating with the cover, a spring urging the cover into open position when the latch releases the same, and a cartridge feeder movable in said casing and cooperating with the latch. 20

5. A cartridge magazine for firearms comprising a casing removably attached to the firearm and having an opening for the insertion of a cartridge pack into the casing, means at the front 25 end of the casing for guiding cartridges into the breech of the firearm, a cover for said opening, means urging the cover to open position, a cartridge feeder movable in said casing, means urging the feeder in the direction of the guide means, a latch cooperating with the cover and the feeder 30 to retain the feeder at the rear end of the casing while releasing the cover and to release the feeder when said latch engages the cover to close the opening, a curved lever pivoted to said casing and engaging a projection on the feeder for moving 35 the latter to latch engaging position, and an operating handle on said lever, the curvature of the lever being adapted to produce uniform resistance of the feeder urging means during the operation of the handle.

6. A cartridge magazine according to claim 1, comprising means operated by closure of the cover to release the cartridges from the cartridge pack.

7. A cartridge magazine according to claim 1 for use with a cartridge pack in which the cartridges are retained by a clip, comprising means in the casing for guiding the cartridges and clip, and in which the casing has a bottom opening 45 for discharge of the clip when emptied. 50
